UNITED STATES PATENT OFFICE.

JAMES G. CRAWFORD, OF BOSTON, MASSACHUSETTS.

MANGLE.

SPECIFICATION forming part of Letters Patent No. 247,486, dated September 27, 1881.

Application filed April 23, 1881. (Model.)

To all whom it may concern:

Be it known that I, JAMES G. CRAWFORD, of Boston, in the county of Suffolk and State of Massachusetts, have invented new and useful Improvements in Mangles, of which the following is a specification.

The nature of the invention, in detail, is described below.

In the accompanying drawings, in which similar letters of reference indicate like parts, Figure 1 is an end elevation of my improved mangle. Fig. 2 is a rear elevation of the same. Fig. 3 is a transverse vertical section.

A is the frame of the machine, A' the table, and B the box or receptacle holding the goods to be smoothed.

C is the larger roll (covered with felt or similar substance) upon the shaft C', to which is fixed the gear-wheel D. This roll is made adjustable, so as to press more or less against the ironing-bed H above it in any convenient manner, preferably by having its shaft-bearings adapted by means of the screw-thread b' on the vertical shaft b, actuated by the bevel-gear c d, (to the shaft e of the latter of which power is applied,) to be raised and lowered in the slots or openings a. This is substantially the adjusting mechanism shown in Letters Patent numbered 238,657, granted to me March 8, 1881.

30 The smaller roll E on the shaft E', whose ends rest in adjustable boxes G, lies above the ironing-bed H, and is rotated by means of the gear-wheel F, secured to the shaft E' and engaged by the gear-wheel D.

35 H is a metallic reciprocating ironing-bed, guided by means of a pair of rollers, I I, supported in arms J. Each arm J (there being one at each end of the ironing-bed) supports two rollers, I I, one of which is above and one below the ironing-bed H, as shown in Fig. 3. Motion is imparted to the bed H by means of the two rods K, pivoted at K' to the ironing-bed, and encircling the eccentrics L upon the horizontal shaft L', to which is fixed the gear-wheel M. This wheel M, by means of the intermediate gear-wheel, N, is engaged by the small gear-wheel O, fixed to the shaft C'.

40 Motion having been imparted, by means of the crank P' and gear-wheel P, to the wheel D, 45 the rolls C E rotate, and the ironing-bed H re-

ciprocates between them. The articles to be smoothed are placed in position—the smaller ones, such as napkins, &c., between the ironing-bed and roll E, and the larger ones, such as sheets, &c., between the ironing-bed and roll C—and are carried from the box B over table A' through the machine. The ironing-bed is so geared that when its movement is with the rolls it moves more slowly than the rolls, thus preventing wrinkling, which would ensue if the movements of the bed and rolls were the same, and aiding in polishing. When its movement is contrary to that of the rolls of course there is no danger of wrinkling.

50 R is a sliding platform extending from front to rear of the machine, resting upon the cross-bars A'' of the frame and guided by the bent pins S, which project into the grooves R'. Secured to this platform R, at the rear side of the machine, is the guiding-plate T, of the peculiar shape shown. The operation of this plate T is as follows: When a large article—such as a sheet, for example—is to be passed between the ironing-bed H and the large roll C the operator (who stands on the side where the box B is placed) pushes the platform R from her until it is in the position shown in Fig. 3. Then when the sheet has passed through—ironed, of course, on one side only—it falls upon the concave portion T'' of the plate T, and is guided back under the roll, when it is seized by the operative, reversed, and the platform R drawn back until the concave portion T'' nearly touches the roll C, to whose shape it conforms. The sheet is then passed through the machine to be ironed on the other side, when it drops upon the portion T' of the plate T, and is guided off into a receptacle placed behind the machine. Thus this guiding-plate T and platform R save traveling around the machine to obtain an article in order to iron it on its reverse side, or else keeping an extra hand for that purpose.

55 It is understood, of course, that heat is applied in the ordinary manner to the interior of the ironing-bed.

Having thus fully described my invention, what I claim, and desire to secure by Letters Patent, is—

1. The combination, with the roll C, shaft C',

and gear D O, the roll E, shaft E', and gear-wheel F, of the curved reciprocating ironing-bed H, rods K, eccentrics L, shaft L', gear M N, arms J, and rollers I, all supported in the frame A, and constructed and arranged substantially as and for the purpose set forth.

2. In combination with the roll C, the guiding-plate T T' T'', of the shape shown, secured

to the sliding platform R, supported in the frame of the machine, substantially as and for the purpose set forth.

JAMES G. CRAWFORD.
